UNITED STATES PATENT OFFICE.

HUBERT E. BAKER, OF MUSKEGON, MICHIGAN, ASSIGNOR TO MANNING, MAXWELL & MOORE, INC., OF MUSKEGON, MICHIGAN.

TRAVELING CRANE.

Application filed April 29, 1927. Serial No. 187,507.

The main objects of this invention are:

First, to provide in a traveling crane an improved spring support.

Second, to provide in a traveling crane of the double truck type an improved spring support which is very compact, does not add to the height of the bridge and is capable of carrying very heavy loads.

Third, to provide in a traveling crane an improved spring structure in which the supporting springs are effectively supported and housed.

Objects pertaining to details and economies of my invention will appear from the description to follow. The invention is pointed out in the claims.

A structure embodying the features of my invention is clearly illustrated in the accompanying drawing forming a part of this application, in which:

Fig. 1 is an end view of a traveling crane embodying the features of my invention, a portion of the footwalk being broken away.

Fig. 2 is a vertical longitudinal section through one of the truck units on a line corresponding to line 2—2 of Figs. 3 and 4.

Fig. 3 is a detail view partially in horizontal section on a line corresponding to line 3—3 of Figs. 1 and 2.

Fig. 4 is a detail vertical section on a line corresponding to line 4—4 of Figs. 1, 2 and 3.

In the embodiment illustrated I provide a bridge structure designated generally by the numeral 1 and comprising bridge members 2 connected at their ends by the beams 3. As the structural details of the bridge structure form no part of this invention they are not fully illustrated or described herein.

The structure illustrated is of the double truck type, that is, there are two trucks at each end, and as these are substantial duplicates a description of one is all that is necessary.

Each truck unit comprises a bolster 4 disposed in the embodiment illustrated at the end of one of the bridge elements 2 and constituting the support for the bridge structure. These bolster members are chambered to receive the inner ends of the wheel carrying members 5. These wheel carrying members are pivoted at 6 within the bolster to project therefrom and are provided with suitable bearing boxes shown conventionally at 7 for the journals 8 of the wheels 9. The

rail on which the wheels travel is shown 55 conventional at 10.

Above their pivots 6 the wheel carrying members 5 are provided with thrust members 11 preferably curved as illustrated to coact with sockets 12 formed centrally of the heads 13. These heads 13 are arranged in opposed pairs and provided with seats 15 for the pairs of coiled springs 16 and 17 which are arranged in nested relation, the ends of the inner springs engaging the positioning studs 18 projecting from the faces of the heads 13.

The heads are connected by a tie rod 19 in the form of a bolt, the head 20 and the nut 21 constituting stops limiting the separate movement of the heads. The heads, however, 70 are slideable on the rod. The head and nut are arranged in recesses 22 disposed centrally.

To limit the pivotal movement of the wheel carrying members on their pivots 6 I 75 provide them with laterally projecting stops 23 which coact with the segmental slots 24 in the bolster, thus preventing excessive movement when relieved of a load, and also retaining the parts in proper relation when 80 the wheels are not supported on the rail.

One of each pair of wheel carrying members is provided with bearings 25, indicated in Fig. 3, for the shaft 26 of the driving pinion 27. This driving pinion coacts with a 85 gear 28 secured to the journal of one of the carrying wheels 9. The driving features, however, are not made a part of the subject matter of this application.

I have illustrated and described my improvements in an embodiment which I consider very practical. As it is believed that the disclosure made will enable those skilled in the art to embody or adapt my improvements as may be desired, modifications and other adaptations are not illustrated or described.

Having thus described my invention what I claim as new and desire to secure by Letters Patent is:

1. In a traveling crane, the combination with a bridge structure, of a truck therefor comprising a chambered bolster, wheels, wheel carrying members pivotally mounted in opposed relation within said bolster to 105 project therefrom and having opposed thrust members above their pivots, a spring unit comprising opposed heads coacting

with said thrust members of said wheel carrying members, said heads having opposed spring seats thereon and opposed studs disposed centrally of their said seats, nested pairs of springs arranged on said seats with the end coils of the inner springs of each nested pair engaging said studs, a tie rod with which said heads are slidably engaged and having stops limiting the outward movement of said heads, and laterally projecting stops on said wheel carrying members disposed above their pivots, said bolster having segmental slots coacting with said stops to limit the movement of said wheel carrying members on their pivots.

2. In a traveling crane, the combination with a bridge structure, of a truck therefor comprising a chambered bolster, wheels, wheel carrying members pivotally mounted in opposed relation within said bolster to project therefrom and having opposed thrust members above their pivots, a spring unit comprising opposed heads coacting with said thrust members of said wheel carrying members, said heads having opposed spring seats thereon and opposed studs disposed centrally of their said seats, nested pairs of springs arranged on said seats with the end coils of the inner springs of each nested pair engaging said studs, and a tie rod with which said heads are slidably engaged and having stops limiting the outward movement of said heads.

3. In a traveling crane, the combination with a bridge structure, of a truck therefor comprising a chambered bolster, wheels, wheel carrying members pivotally mounted in opposed relation within said bolster to project therefrom and having opposed thrust members above their pivots, a spring unit comprising opposed heads coacting with said thrust members of said wheel carrying members, a spring element between said heads, a tie rod with which said heads are slidably engaged and having stops limiting the outward movement of said heads, and laterally projecting stops on said wheel carrying members disposed above their pivots, said bolster having segmental slots coacting with said stops to limit the movement of said wheel carrying members on their pivots.

4. In a traveling crane, the combination with a bridge structure, of a truck therefor comprising a chambered bolster, wheels, wheel carrying members pivotally mounted in opposed relation within said bolster to project therefrom and having opposed thrust members above their pivots, a spring unit comprising opposed heads coacting with said thrust members of said wheel carrying members, a spring element between said heads, and a tie rod with which said heads are slidably engaged and having stops limiting the outward movement of said heads.

5. In a traveling crane, the combination

with a bridge structure, of a truck therefor comprising a chambered bolster, wheels, wheel carrying members pivotally mounted in opposed relation within said bolster to project therefrom and having opposed thrust members above their pivots, a spring unit comprising opposed heads coacting with said thrust members of said wheel carrying members, and a spring element between said heads.

6. In a traveling crane, the combination with a bridge structure, of a truck therefor comprising a chambered bolster, wheels, wheel carrying members pivotally mounted in opposed relation within said bolster to project therefrom and having opposed thrust members above their pivots, a spring unit coacting with said thrust members of said wheel carrying members, and laterally projecting stops on said wheel carrying members disposed above their pivots, said bolster having segmental slots coacting with said stops to limit the movement of said wheel carrying members on their pivots.

7. In a traveling crane, the combination with a bridge structure, of a truck therefor comprising a chambered bolster, wheels, wheel carrying members pivotally mounted in opposed relation within said bolster to project therefrom and having opposed thrust members above their pivots, and a spring unit coacting with said thrust members of said wheel carrying members.

8. In a traveling crane, the combination of a bridge structure, a supporting bolster therefor, wheel carrying members pivotally mounted on said supporting bolster in opposed relation, said wheel carrying members being provided with opposed thrust members, and coiled springs arranged between said thrust members whereby said wheel carrying members are yieldingly supported on their pivots.

9. In a traveling crane, the combination of a pair of bridge members connected in spaced relation by beams disposed at the end of the bridge members, supporting bolsters disposed at the ends of the beams, wheel carrying members pivotally mounted on said supporting bolsters in opposed pairs, said wheel carrying members being provided with opposed thrust members, and coiled springs arranged between said thrust members whereby said wheel carrying members are yieldingly supported on their pivots.

10. In a traveling crane, the combination of a pair of bridge members connected in spaced relation by beams disposed at the end of the bridge members, supporting bolsters disposed at the ends of the beams, wheel carrying members pivotally mounted on said supporting bolsters in opposed pairs, and springs arranged between said wheel carrying members whereby they are yieldingly supported on their pivots.

11. In a traveling crane, the combination of a pair of bridge members connected in spaced relation by beams disposed at the ends thereof, supporting bolsters disposed at the ends of said bridge members, wheels, wheel carrying members pivotally mounted on said bolsters in spaced pairs, and springs

arranged between said spring carrying members whereby they are yieldingly supported on their pivots.

In witness whereof I have hereunto set my hand.

HUBERT E. BAKER.
